UNITED STATES PATENT OFFICE.

JAMES F. MIRRIELES, OF CINCINNATI, OHIO, ASSIGNOR TO AVEY DRILLING MACHINE CO., OF CINCINNATI, OHIO, A CORPORATION OF OHIO.

STROKE-LIMITING DEVICE FOR AUTOMATIC MACHINES.

Application filed February 7, 1921. Serial No. 443,031.

To all whom it may concern:

Be it known that I, JAMES F. MIRRIELES, a citizen of the United States, residing at Cincinnati, in the county of Hamilton and 5 State of Ohio, have invented certain new and useful Improvements in Stroke-Limiting Devices for Automatic Machines, of which the following is a specification.

This invention relates to improvements in 10 automatic machinery, but more particularly to stroke limiting devices for the same and has for its primary object to provide a simple and efficient mechanism for automatically stopping the operation of the machine 15 or a portion thereof upon the completion of a predetermined number of strokes, cycles or operations.

Another important object is to provide 20 controlling means for the tool feeding mechanism which will cause the machine to operate either as a full or a limited automatic.

Further objects of the invention are to provide a work feed controlled by the movement of the tool, and to produce a stroke 25 limiting device which may be readily attached to machines already in use.

In order to fully illustrate the construction and mode of operation of my invention, I have embodied the same in a reciprocating 30 drilling machine of the automatic type. The particular drilling machine construction adopted forms the subject matter of United States patent to John J. Hey, No. 1,216,689, granted on Feb. 20, 1917, and reference may be had thereto for complete 35 description of the drilling mechanism. The present invention is particularly adapted for use in connection with the improved feed mechanism for drilling machines forming the subject matter of my United States Patent, No. 1,388,875, granted on August 40, 1921. It will be readily evident that my invention is equally applicable to any machine having a reciprocating part required 45 to make a predetermined number of cycles and to then be automatically stopped.

The many other objects and advantages 50 of my invention will be better understood by reference to the following specification when considered in connection with the accompanying drawings showing a selected embodiment thereof in which:

Fig. 1 is a side elevation of a drilling 55 machine with my invention embodied there-

Fig. 2 is a section on the line 2—2 of Fig. 4.

Fig. 3 is a detail view of a portion of the mechanism showing the control handle for the feeding mechanism. 60

Fig. 4 is a section on the line 4—4 of Fig. 2.

Fig. 5 is a section on the line 5—5 of Fig. 6.

Fig. 6 is a section on the line 6—6 of Fig. 5. 65

Fig. 7 is a section on the line 7—7 of Fig. 8.

Fig. 8 is a section on the line 8—8 of Fig. 7. 70

Fig. 9 is a diagrammatical view of the clutch mechanism.

Referring to the drawings, my invention is embodied in an automatic drilling machine having the usual vertical standard 10, 75 base 11, rotating spindle 12 carried by the reciprocating spindle sleeve 12', and actuating mechanism for the spindle. A weight 13 automatically returns the spindle to its raised position upon completion of its downward movement. The power feed mechanism illustrated for effecting the working strokes of the drill spindle is similar to that set forth in the patent to Hey No. 1,216,689. 80

The particular machine shown in the 85 drawings is intended for drilling three oil holes in the side pinions of a differential. The pinion 14 to be drilled is mounted on the outer extremity of the work feeding shaft 15 in the casing 16 secured upon the usual work table 17 of the machine. A bevel gear 18 on the shaft 15 is driven by the gear 19 on the sleeve 20 keyed upon the shaft 21. A gear 22 on the sleeve 20 meshes with a gear 23 on the shaft 24 disposed in 90 parallel relation with the shaft 21. An escapement ratchet 25 on the sleeve 20 is engaged by the corresponding escapement anchor 26 controlled by the trip 27. This trip 27 is pivotally mounted at 28 on the lower end portion of the reciprocating plunger 29 and actuated by the adjustable screw 30 set in the casing 16. A spring 31 presses the plunger 29 into 95 engagement with the escapement member 26. A flat spring 27' forces the trip 27 into 100 engagement with the escapement member 26.

A ratchet 31 is keyed upon the shaft 24 and actuated by the pawl 32 pivoted at 33 on the plunger 29. A spring 35 presses against the pawl 32 to retain the same in en- 110

gagement with the ratchet 31. A flat spring 36 engages the ratchet 31 to permit rotation of this ratchet in one direction only.

A collar 37 fits about the spindle sleeve 12' and is secured in place thereon. A casing 40 is formed on this collar and means for controlling the spindle feeding mechanism is mounted therein. A shaft 39 is mounted in suitable bearings in the casing 40 and an eccentric 41 is secured upon this shaft. A sleeve 41' fits about this shaft 39 and is free to rotate relative thereto. A cam 42 and a ratchet 43 are fixed on this sleeve. A rocking lever 44 pivoted intermediate its ends on the stud shaft 45, has a wedge shaped projection 46 formed on its inner end to fit within one of the peripheral indentations 47 on the cam 42. The number and disposition of the teeth on the ratchet relative to the notches on the cam is dependent on the number of operations desired in each series. For example, there are three holes to be drilled in each pinion 14 placed upon the work shaft so that the drill must perform three operations thereon and then stop. The ratchet must therefore advance the distance of three teeth to advance the cam from one notch to the next. The projection 46 on the inner end of the lever 44 is pressed against the periphery of the cam 42 by the spring-pressed trip plunger 48 acting against the outer extremity of this lever. A spring-pressed pawl 49 is carried by a bar 50 that is mounted to slide vertically in the casing 40. The lower extremity of this bar 50 projects through the bottom plate of the casing 40 and is provided with an adjustable stop collar 51 for limiting the relative movement of the bar and casing. A notch 52 is formed in the upper extremity of this bar 50 to receive and fit the wedge shaped end of a spring pressed plunger 52' carried by a bracket 53 on the head 54 in which the reciprocating spindle sleeve is guided. The plunger 52' rides out of the notch when the under face of the casing 40 strikes stop 51 during the downward movement of the spindle. At the end of the up stroke of the spindle, the plunger 52' re-engages the notch of the bar 50. The latter is thus upheld during the initial portion of the down or working stroke of the spindle, spindle sleeve and parts mounted thereon, and the ratchet 43, during its downward movement relative to the bar 50, is rotated one step by the pawl 49 on the bar and the cam 42 is correspondingly advanced. A spring-pressed holding dog 55 prevents rotation of the ratchet and cam in the opposite direction. When the casing 40 strikes the stop 51 and disengages the bar 50 from the catch plunger 52', the bar drops by gravity and pawl 49 moves idly past a tooth of the ratchet. The cam 42 is thus advanced one

step at each stroke of the spindle. It will be understood that when one of the notches 47 of the cam is in line with the inner lever 44, the trip plunger 48 will be in its lowered or inoperative condition, but that when the inner end 44 is engaged by a high portion of the cam, the trip plunger will be in its raised, operative condition.

A pin 60 projects laterally from the lever 44 beneath the eccentric 41, and a control handle 61 is secured to the outer extremity of the shaft 39 on which this eccentric is mounted. A spring pressed plunger 62 in this handle is adapted to engage recesses 63 on the face of the casing to retain the arm in either its raised or lowered position. The eccentric is out of engagement with the pin when the handle 61 is in its raised position, but when this handle is swung into its lowered position, the eccentric engages the pin and depresses the inner end of the lever 44, lifting the trip plunger 48 and maintaining it in its raised position until the handle is returned to its raised position.

The upper extremity of the plunger 29 is secured to the bracket 64 carried by the collar 37. The corresponding extremity of the plunger 34 is adapted to contact with the bottom plate 65 on the collar to force this plunger downwardly and compress the spring 66 as the collar moves downwardly with the spindle 12.

In the operation of the device the spindle is fed downwardly by the feeding mechanism controlled by the lever 75. This lever is provided with an angularly disposed cam portion 76, shown in Figs. 1 and 9, which is engaged on its upper inclined face by the trip 77 adjustably mounted on the spindle sleeve 12' at the end of the working stroke of the spindle. This trip causes the lever 75 to swing on its pivot 78 and the feed clutch 79 to be disengaged. The spindle is then automatically raised by the weight 13 in the usual manner. At the completion of the up-stroke the trip 48, if in its raised position, engages the under inclined face of the plate 76 on the lever 75, moving the clutch 79 into engagement, and repeating the feeding of the spindle. This full automatic action of the spindle will continue as long as the plunger 48 remains in its raised position to shift the feed control lever 75. If no automatic stopping is desired, the handle 61 should be moved to its lowered position and the trip plunger 48 will remain raised. The upward movement of the drill spindle effected by the counterweight 13 is limited by the engagement of the collar 37 on the spindle sleeve with the guiding head 54. If the trip plunger 48 is in its raised, operative condition, it will engage and operate the clutch control lever 75 just before the spindle reaches the upper limit of its movement. But, if the trip is in its lowered,

inoperative condition, the upper movement of the spindle is arrested before the trip engages the control lever.

To cause the spindle to be automatically stopped at the completion of a predetermined number of operations, the handle 61 should be placed in the raised position which moves the eccentric out of operative relation with the pin 60 on the lever 44 and permits this lever to rock upon its fulcrum. At the completion of the predetermined series of operations, the control lever 75 will not be actuated to start the down-stroke of the spindle because the projection 46 on the lever 44 has entered one of the notches 47 in the cam 42, as indicated in Fig. 4, permitting the trip plunger 48 to drop to its depressed position where it can not engage and trip the handle 75.

The operation of the machine, assuming the parts to be in the position shown in Figs. 1 and 4, with the spindle at the upper limit of its movement, is as follows: Power feed mechanism is engaged by manually shifting the clutch 79 by means of the lever 75. During the initial downward movement of the drill spindle, the bar 50 is momentarily upheld, as described, to advance the ratchet 43 and cam 42 one step and thereby shift the trip plunger 48 from its inoperative to its operative position. The downward movement or working stroke of the drill spindle and sleeve also move the plungers 29 and 34 of the work feed mechanism downwardly. During the downward movement of the plunger 29 the trip 27 thereon moves idly by the escapement anchor 26 and, during the downward movement of the plunger 34, the spring 66 is compressed and the pawl 32 thereon is moved idly by one of the teeth of the ratchet 31.

At the end of the down or working stroke of the spindle, the trip 77, which may be adjusted to vary the depth of the working stroke, engages the lever 75 and disengages the feed mechanism from the spindle so that the latter is returned by the counterweight 13. During the upward movement of the spindle, the plunger 29 of the work feed mechanism rises but the plunger 34 is held depressed with the spring 66 under compression until the trip 27 engages and rocks the anchor 26 to thereby disengage the tooth 82 thereon from a tooth 81 of the escapement wheel 25. The spring 66 is then effective to advance the escapement wheel and parts connected thereto, including the work which is being operated upon. On the continued upward movement of the plunger 29 the screw 30 disengages the trip 27 from the anchor 26 so that the latter is again depressed by the spring plunger 26' and the tooth 82 of the anchor engages the next tooth of the escapement wheel, the anchor and escapement wheel being arranged to permit the passage

of only one tooth at a time and insure the proper feed of the work. In the particular instance illustrated, the holes to be drilled in the pinion 14 are spaced 120 degrees apart so that the teeth 81 on the escapement wheel 70 are three in number and likewise spaced, but the number and spaces of these teeth can be varied if desired, to conform to the number and spacing of the holes to be drilled in the particular piece of work. At the end of 75 the return stroke of the spindle, the trip plunger 48, being in its raised or operative position, re-engages the clutch of the power feed mechanism, as described, to effect the next working stroke.

The automatic reciprocation of the spindle continues until the cam 42 has been advanced by the ratchet 43 sufficiently to bring the projection 46 on the lever 44 into the next notch 47 therein, which, in the present operation, is a three tooth distance, and the spindle has returned to its raised position. The plunger 48, now being in its depressed position, does not actuate the control handle 75 so that the spindle stops at the end of its up stroke and remains in this position until manually started for the next series of operations in the manner described.

The form of the work feed mechanism would naturally be varied to suit the particular operation which it is designed to perform, but the principles of construction and operation are the same in all cases. Likewise the cam 42 in the stroke limiting device would be designed to produce the 100 desired number of operations of the spindle in the series.

Machines of this type are generally operated progressively. The operator loads the first spindle and engages the feed. He then successively repeats this operation at the other spindles under his charge. By the time that the last spindle has been loaded and started, the first spindle should have completed its operations on the work to 110 come to rest. The operator does not need to watch each spindle to insure that it is stopped at the proper moment.

The stroke limiting device is the connecting link between the automatic spindle feed 115 and the automatic work feed and without it fixtures for accomplishing the automatic feeding of the work cannot be operated at their full capacity, and the danger of spoiling work by over drilling would render some 120 fixtures of this type impracticable. Many other changes in the construction and arrangement of parts might readily be made without departing from the spirit of my invention, and I reserve the right to make 125 all such as fairly fall within the scope of the following claims.

I claim as my invention:

1. A machine of the class described comprising a reciprocating member, actuating 130

means for said member, and means operated by the movement of said member for automatically releasing said member from said actuating means upon the completion of a predetermined plurality of reciprocations of said member.

2. A machine of the class described comprising a work supporting member, a tool carrying member, one of said members reciprocating relative to the other, actuating means for said reciprocating member, and means operated by the movement of said reciprocating member for automatically releasing said reciprocating member from said actuating means upon the completion of a predetermined plurality of reciprocations of said member.

3. A machine of the class described comprising a work support, a reciprocating tool holder, means for actuating said holder, and means controlled by the movement of said holder for automatically disengaging said holder from said actuating means upon the completion of a predetermined plurality of strokes of said holder.

4. A machine of the class described comprising a work support, a reciprocating tool holder, actuating mechanism for said holder including a clutch, means for automatically shifting said clutch to initiate each working stroke and each return stroke of said tool holder and means controlled by the movement of said holder for preventing the continued operation of said automatic clutch-shifting means upon the completion of a predetermined number of successive strokes of said tool holder.

5. In a machine of the class described, the combination with a reciprocating drill spindle, actuating means therefor and stroke limiting means for the spindle comprising a rotary cam, means controlled by the movement of the spindle for intermittently advancing said cam, a member constantly engaging the surface of said cam and means controlled by said member for arresting the operation of the spindle upon the completion of a number of successive strokes as predetermined by the conformation of the cam surface.

6. A machine of the class described comprising, a reciprocating tool holder, a work feed operated by the movement of said holder, actuating means for said holder, and means actuated by the movement of said holder for automatically releasing said holder from said actuating means upon the completion of a predetermined number of successive reciprocations of said holder.

60 7. In a machine of the class described, the combination with a reciprocating member and operating mechanism therefor, of trips connected to said member and cooperating with said mechanism to start the working and return strokes respectively of said mem-

ber and means for automatically disabling said working stroke starting trip upon the completion of a predetermined number of successive reciprocations of said member.

8. A machine of the class described comprising a spindle, means for feeding said spindle toward the work, means for automatically stopping said feeding means at the end of the forward stroke, means for returning said tool to its initial position, means for automatically starting said feeding upon the completion of the return stroke, and means controlled by the movement of said spindle for rendering said starting means inoperative at the completion of a predetermined plurality of strokes of said spindle.

9. A machine of the class described comprising a tool holder, means for feeding said holder toward the work, means for stopping said feeding means at the completion of the forward stroke of said holder, means for returning said holder to its initial position, a trip positioned to automatically start said feeding means at the completion of the return stroke, and means for automatically moving said trip out of operative position upon the completion of a predetermined plurality of strokes of said tool holder.

10. In a machine of the class described, a reciprocating tool, means for effecting the working and return strokes of said tool, work feed mechanism controlled by the strokes of said tool, a controller for said tool actuating means, means connected to said reciprocating tool for automatically shifting said controller at the ends of the working and return strokes of said tool, and means for preventing the operation of said controller shifting means upon the completion of a predetermined number of successive operations of said tool.

11. A machine of the class described comprising a reciprocating spindle, power-actuated feed mechanism for effecting the working strokes of said spindle, a controller for initiating the operation of said feed mechanism, a trip connected to said spindle for operating said controller at the ends of the return strokes of said spindle, a cam controlling the operation of said trip and actuating means for said cam controlled by the movement of said spindle.

12. A machine of the class described comprising a reciprocating spindle, feed mechanism for said spindle, controlling means for said feed mechanism, means for actuating said controlling means at the completion of the forward stroke of the spindle to release said spindle, means for returning said spindle to its initial position, a trip for actuating said controlling means at the completion of the forward stroke to reengage said feeding mechanism, and means for automatically moving said trip out of operative

position at the completion of a predetermined number of strokes of said spindle including a cam actuated by the movement of said spindle.

- 5 13. Stroke limiting means for drilling machines and the like, comprising in combination a reciprocating member, actuating means therefor including a controlling clutch, a trip device connected to said member and adapted, in operative condition, to actuate said clutch, a cam for moving said trip device into and out of operative condition, and means operative upon the reciprocation of said member for advancing said cam.

- 10 14. A stroke limiting device comprising in combination a reciprocating drill spindle, power actuated feed mechanism therefor, a clutch controlling said feed mechanism, a trip connected to said spindle for actuating said clutch, a cam for throwing said trip into and out of operative position and means controlled by the operation of said feed mechanism for positioning said cam.

- 15 15. A stroke limiting device for automatic machinery comprising a spring pressed trip, a lever co-acting with said trip to move the same into operative position against the action of said spring, a cam controlling the movement of said lever, and means for providing an intermittent actuation of said cam.

- 20 16. A stroke limiting device for automatic machinery comprising a trip, a lever co-acting with said trip to move the same into operative position, a cam controlling the movement of said lever, and means for actuating said cam to provide periodic movement of said trip.

- 25 17. A stroke limiting device for automatic machinery comprising a trip, a lever co-acting with said trip to move the same into operative position, a cam controlling the movement of said lever, and means for controlling said trip independently of said cam.

- 30 18. In a machine of the class described, the combination with a reciprocating member, of a stroke limiting device for said member comprising a trip movable into and out of operative position to control the actuation of said member, and a cam controlling said trip and actuated by the movement of said member.

- 35 19. In a machine of the class described, the combination with a reciprocating member and actuating means therefor, of a stroke limiting device for controlling the actuation of said member comprising a trip carried by said member and movable into and out of operative relation with said actuating means, a cam controlling the movement of said trip, and a plunger actuated by the movement of said member to impart to said cam an intermittent advance.

- 40 20. In a machine of the class described,

the combination with a reciprocating member, and actuating means therefor, of a stroke limiting device for controlling the actuation of said member, comprising a trip movable into and out of operative relation with said actuating means, a cam controlling said trip and actuated by the movement of said member, and means for controlling said trip independently of said cam.

45 21. In a machine of the class described, the combination with a reciprocating member and actuating means therefor, of a stroke limiting device for said member comprising a trip movable into and out of operative relation with said actuating means, a cam controlling said trip and actuated by the movement of said member, and means for manually controlling the movement of said trip independently of said cam.

50 22. In a machine of the class described, the combination with a reciprocating member and actuating means therefor, of a stroke limiting device for said member comprising a trip carried by said member and movable into and out of operative relation with said actuating means to control the operation thereof, a lever controlling said trip, and a cam controlling said lever and actuated by the movement of said member to provide a periodic operation of said trip.

55 23. Stroke limiting means for drilling machine comprising in combination, a drill spindle, a supporting sleeve therefor, power actuated feed mechanism for said sleeve, a controlling clutch for said feed mechanism, trips mounted on said sleeve, means controlled thereby for engaging and disengaging said clutch at the ends of the return and working strokes respectively of the spindle, and means mounted on said sleeve and controlled by the movement thereof for automatically disabling said clutch engaging trip.

60 24. In drilling machines, the combination of a work support, a drill spindle, a reciprocating sleeve wherein said drill spindle is mounted, power actuated feed mechanism for said sleeve, a controlling clutch for said mechanism, trips on said sleeve for automatically shifting said clutch at the ends of the working and return strokes of the spindle, means on said sleeve controlled by the movement thereof for disabling one of said trips, and work feed mechanism on said work support controlled by the reciprocating movements of said sleeve.

65 25. Stroke limiting means for drilling machines and the like, comprising in combination a reciprocating member, power actuated feed mechanism for effecting the working strokes of said member, means for effecting the return strokes thereof, automatically acting trip devices for respectively engaging and disengaging said feed mechanism to initiate and arrest each working

stroke of said member and means controlled by the successive movements of said reciprocating member for preventing the operation of said feed engaging trip device upon the completion of a predetermined number of successive working strokes.

26. In drilling machine, the combination of a drill spindle, power actuated feed mechanism for effecting the working strokes of said spindle, means for effecting the return strokes thereof, trip devices connected to said spindle for automatically engaging and disengaging said feed mechanism at the beginning and end of each working stroke, a member intermittently advanced by the movements of said spindle for preventing the operation of said feed engaging trip device upon the completion of a predetermined number of successive working strokes, and

work feed mechanism intermittently controlled by the reciprocating movements of said spindle.

27. Stroke limiting means for drilling machines and the like, comprising in combination a reciprocating tool holder, power actuated feed mechanism therefor, automatically acting trip devices for respectively engaging and disengaging the feed mechanism at the beginning and end of each working stroke of the tool holder, means for manually shifting said feed engaging trip device into and out of operative condition and means controlled by the successive movements of the tool holder for automatically shifting the latter trip device into and out of operative condition.

JAMES F. MIRRIELES.
